WARP-KNITTING MACHINE

Application filed July 19, 1927, Serial No. 206,833, and in Germany December 12, 1926

This invention relates to warp-knitting machines, and according thereto means are provided whereby one or more wefts can be inserted into the fabric between the warp 5 threads.

Many different kinds and patterns of knitted fabrics having rib, lining, covering, tinsel, or pattern warp threads (with or without mesh patterns), may be made in accordance with the invention, such, for example, 10 as corset fabrics, elastic bandage material having rubber threads, stuff similar to tapestry or brocade for furniture, and hangings, curtains, covers, rugs, and pluses of various 15 kinds. Nevertheless the same machine can be used when required, without structural alteration, in the usual way, that is for the manufacture of known kinds of fabrics.

In order that the invention may be clearly 20 understood and readily carried into practice, we have appended hereto two sheets of drawings, in which:—

Fig. 1 is a sectional end view of a portion 25 of a machine embodying the invention; and

Fig. 2 is a fragmentary side view of the weft guide members and the means for operating them.

The guides *a* for the knitted warp threads 30 *K*, *K'*, *K*², *K*³ are carried by bars suspended in the usual way from a swinging beam *b*. In a space formed by the omission of one of the usual thread guide bars, is arranged a bar *c* provided with weft guide fingers *e*, *e'* mounted 35 on supports having tongues or ribs sliding in longitudinal grooves of channels *d*, *d'*. These fingers, which guide the wefts *s'*, *s*², are positioned according to the breadth of the fabric, and are actuated by the driving pins or tappets *f*, *f'*.

The driving pins or tappets *f*, *f'* are fastened to bars *g*, *g'*, which may be, similarly to the thread guide bars, movable laterally, but are also pivotally mounted so that either 45 or both of the tappets can be put out of action at will. By displacement of the bars *g*, *g'*, the tappets *f*, *f'* can be swung into either of the positions shown in full lines and dotted lines respectively, so that they 50 will strike either of the thread guides *e*, *e'*.

In the position of the parts shown in the

drawings, crossed-double wefts *S*, *S'*, *S*² are being inserted, i. e. wefts are being inserted simultaneously from both sides of the fabric. If the driving pins or tappets *f*, *f'* are moved into the positions shown in dotted 55 lines, they run without working, that is to say, neither of the two weft guide fingers is actuated, and no weft is inserted. If only the upper or the lower driving pin or tappet *f*, *f'* is moved around out of the position 60 shown in the drawings, then one only of the two wefts is inserted.

The driving pins *f*, *f'* may, of course, be shaped differently, and the bars *g*, *g'* can be operated by any suitable means other than 65 a cam drum.

In the case of a single instead of a double weft arrangement, a single weft thread guide finger may simply be secured to a bar, which is suspended similar to the thread guide 70 bars, from a bar on which it can freely slide longitudinally.

The number of the thread guide bars may, of course, be varied. For the most usual fabrics the thread guide bars 1, 2 are not 75 utilized, that is to say, they carry no warp threads.

The weft thread arrangement may be provided between others of the thread guide bars instead of between the ones shown; it is also possible to provide several such devices in different positions at the same time. Moreover, a known kind of weft arrangement *h*, preferably a double one, may also 85 be provided in front of the needle rail, for laying an ordinary weft thread *s*.

If two weft arrangements according to the invention are provided, or if one such arrangement, and another weft arrangement in 90 front of the needle rail are provided, the advantages are obtained that with only one latch needle rail, front and back wefts can be inserted at the same time. That is to say, one weft is inserted by means of the device *h* in front of the warp *K*, and the other weft is inserted by means of device *e*, *e'* behind the warp *K*, so that the two weft threads are bound by one and the same meshes, but are yet separated by the warp *K* lying be- 100

tween them; this arrangement is especially suitable for the manufacture of double pluses.

If desired, the machine may be built 5 double-sided, that is, have a second latch needle rail and a corresponding weft device or devices facing the first. It is then possible to manufacture tubular knitted materials of various kinds.

10 The weft guide fingers do not necessarily need always to run across the whole breadth of the fabric, since the operating means may be such that the wefts only run across a part of the whole width of the fabric.

15 It should be understood that the above described construction is not essential to the invention. It should further be understood that in a fabric having several wefts, the various wefts may be laid either simultaneously or alternately by suitable arrangement 20 of the operating cams and other mechanism.

What we claim is:—

1. A warp knitting machine, comprising in combination, a latch needle bar, a plurality of warp thread guides disposed in parallel relation, means operative intermediate the formation of successive stitches for laying wefts between the warp threads carried by said guides, and means also operative intermediate the formation of successive stitches for laying other wefts on the outer side of said warp threads.

2. A warp knitting machine, comprising in combination, a needle bar, a series of parallel movable bars carrying cooperating warp thread guides, another parallel movable bar disposed between a pair of said first bars, weft guide members mounted on said last bar for movement longitudinally of the bar, 35 and means mounted for reciprocation in a direction parallel with said bar and adapted to engage said guide members thereby to move the same.

3. A warp knitting machine, comprising in combination, a needle bar, a series of parallel movable bars carrying cooperating warp thread guides, another parallel movable bar disposed between a pair of said first bars, weft guide members mounted on said last bar 45 for movement longitudinally of the bar, means mounted for reciprocation in a direction parallel with said bar and adapted to engage said guide members thereby to move the same, and mechanism in front of the 50 needle bar for inserting weft threads independently of said guide members.

4. A warp knitting machine, comprising in combination, a needle bar, a series of parallel movable bars carrying cooperating warp thread guides, another parallel movable bar disposed between a pair of said first bars and provided in opposite sides thereof with longitudinally extending guide channels, supporting members having ribs seated in said channels for movement longitudinally therein,

weft guide fingers secured to said supporting members, and tappets mounted adjacent to said bar for reciprocation longitudinally of the bar and adapted to engage said supporting members thereby to move said weft guide fingers.

5. A warp knitting machine, comprising in combination, a needle bar, a series of parallel movable bars carrying cooperating warp thread guides, another parallel movable bar disposed between a pair of said first bars and provided in opposite sides thereof with longitudinally extending guide channels, supporting members having ribs seated in said channel for movement longitudinally therein, weft guide fingers secured to said supporting members, and tappets mounted adjacent to said bar for reciprocation longitudinally of the bar and adapted to engage said supporting members thereby to move said weft guide fingers, said tappets being angularly adjustable into and out of engaging position thereby to selectively operate said weft guide fingers.

In testimony whereof we have signed our names to this specification.

THEODOR VORCK.
PAUL ZIMMERMANN.
